UNITED STATES PATENT OFFICE.

NATHANIEL S. KEITH, OF NEW YORK, N. Y.

ELECTRIC-LIGHT REGULATOR.

SPECIFICATION forming part of Letters Patent No. 257,588, dated May 9, 1882.

Application filed July 27, 1881. (No model.)

To all whom it may concern:

Be it known that I, NATHANIEL S. KEITH, a citizen of the United States, residing at New York, in the county of New York and State of New York, have invented a new and useful 5 Electric-Light Regulator, of which the following is a specification.

My invention relates to the feeding and regulating devices of electric lamps; and its object is to produce a feeding mechanism that shall be perfectly steady and uniform in its action, and shall be free from the defects of overfeeding, vibration of the electro-magnetic supporting devices for the carbon, accidental 15 release of the carbon-carrying rod by a sudden jar communicated to the lamp, and other disadvantages incident to the constructions now in general use.

In carrying out my invention I make use of an electro-magnetic motor in a derived circuit, which is geared or connected to the carbon-carrier, so that the movement of the latter in both directions is dependent wholly upon the movement of the motor. The reversal of movement in the carbon-carrier is produced either 25 by positively reversing the direction of movement of the electro-magnetic motor or by operating a reversing-clutch interposed in the train of gear between the motor and the carbon-carrier, the reversal being in either case dependent upon the movement of devices actuated and controlled by electro-magnets placed in a derived circuit to the arc and in the main or principal circuit with the carbons.

In the accompanying drawings, Figure 1 is 35 a side elevation, partly in section, of my lamp. Fig. 2 is a diagram illustrating the circuits in the motor and reversing device more in detail. Fig. 3 shows a modification of the devices for 40 reversing the motor in response to the changes in the length of arc. Figs. 4 and 5 show in side and plan view a modified arrangement for reversing the movement of the carbon-carrier without reversing the direction of rotation of the motor-armature.

Referring to Fig. 1, A and B represent the bottom and top plates of the lamp frame or casing. From the lower plate, B, the lower-carbon carrier is suspended in the usual manner. The upper-carbon carrier, C, is provided 50 with a rack, which gears with a pinion, c, upon

the wheel of a worm-gear, D E. The worm E is formed upon the shaft, or an extension of the shaft, of an electro-magnetic motor, F, which is fed by a derived circuit, in the manner to be presently explained. 55

The motor here shown consists of three sets of electro-magnets, 1, 2, and 3, as shown in Fig. 2, placed symmetrically on a shaft and rotating within a rectangular casing, G, of iron. 60 The commutator of the motor is of the construction described in the patent to C. J. B. Gaume, No. 211,985, dated February 4, 1879; and it consists of a series of plates or segments, every third one of which is joined to the same metallic disk or plate, which in turn is electrically connected to one of the electro-magnets 1 2 3. Thus, referring to Fig. 2, the segments marked 1 are electrically connected to one terminal of the electro-magnet 1, the segments marked 2 65 and 3 in a similar manner to the electro-magnets 2 and 3 respectively. The other terminals of the electro-magnets are joined together and to the shaft of the machine, which is in electrical connection with the frame of the lamp 70 and the binding-post P.

H and H' represent commutator-wheels bearing upon the segments and electrically connected to contact-points 5 and 6, through which the circuit is closed by the action of the regulating electro-magnets. When the circuit is closed through H and 5 the motor is caused to 75 rotate in a direction indicated by the arrow, thus allowing the upper carbon to move downward by gravity, so as to shorten the distance 80 between it and the lower carbon. In this operation the movement of the carrier depends entirely upon the movements of the motor. In the construction here shown the speed of movement of the last wheel of the train may be sufficient to increase the speed of movement of the carrier beyond that which would naturally belong to it if gravity alone acted, and the motor 85 may thus act as a propelling motor. If, however, the speed of the last wheel of the train 90 be less than that which would naturally belong to the carrier, the motor will act partially to retard the carrier; but in both cases, as will readily be seen, the carrier moves with the motor, and is dependent entirely upon such motor for 95 its feeding movement. When the circuit through H and 5 is broken and that through 100

- H' and 6 closed the direction of rotation of the armature-magnets is reversed, thus lifting the upper carbon and lengthening the arc. The reversal of the motor is due to the fact that the 5 wheel H' is placed so as to bear upon a segment of the set adjoining that upon which H bears. In the position of the parts shown in Fig. 2, H and H' are arranged to bear simultaneously upon segments 3 and 2 respectively, 10 so that if the circuit be closed through H the magnet 3 will be attracted toward the side of the case, thus setting up a rotation in a direction indicated by the arrow, while, vice versa, if the circuit be closed through H' and 2 the 15 magnet 2 will be attracted toward the side of the case, and the several magnets will be drawn toward the sides of the case in the succession 2 3 1, thus producing rotation in the opposite direction.
- 20 K and L represent main and derived circuit magnets respectively, arranged as usual, the one, K, in direct circuit with the arc, and the other, L, in a derived circuit around the arc. These electro-magnets act in opposition to one 25 another upon an armature-lever, M, which is electrically connected to the binding-post N, and is adapted to make electrical contact with the point 5 or the point 6 under the preponderating attraction of K or L.
- 30 The circuits through the lamp are as follows: From the post P in electrical contact with the frame of the lamp the main circuit is to carbon-carrier C, upper carbon, lower carbon, supporting-rod R, insulated from the frame, electro- 35 magnet K, and to exit-post N.
- The path of the current through the derived-circuit magnet L is from the post P, frame of the lamp, wire 7, connected to the frame, coils of L, wire 8, attached to the insulated support 40 R' of the armature-lever, wire 9 to post N.
- The derived circuit which feeds the motor F is from P to the shaft of the motor, through the electro-magnets (whose terminals branch from the shaft) to the commutator; thence through 45 wheel H or H', wire 10 or 11, point 6 or 5, armature-lever M, wire 9, and to post N.
- The operation of the devices is as follows: The carbons being in contact, when the current passes the electro-magnet K draws down its 50 end of the armature-lever and closes the derived circuit containing the motor through H', 11, 6, and 9. The motor thereupon begins to revolve in a direction to raise the upper carbon and form the arc. So soon as the arc begins to lengthen beyond the proper point its 55 resistance increases sufficiently to cause the attractive effects of L, assisted by retractor-weight W, or a spring, to preponderate, thus breaking the circuit of the motor through H', 60 and closing its circuit through the other commutator-wheel, H, through 10, 5, M, and 9, and reversing the direction of the rotation of the motor, so that the carbon now moves downward and shortens the arc to the regulated 65 point. When the armature-lever is in an intermediate position the friction of the worm-

gear prevents the upper carbon from falling by gravity. The same cause prevents the carbon from being accidentally fed by a jar or concussion. Should the lamp be started with 70 the carbons out of contact, the armature-lever M would, when the current passes, be held in contact with stop 5, thus preserving the circuit through H and causing the motor to rotate in the proper direction for propelling the carbon 75 downward. This movement would continue until the carbons are brought into contact, whereupon the magnet K would close contact 80 6, and the motor would reverse its movement and separate the carbons to form the arc. 85 When the lamp is burning with an arc of the proper length the attractive effects upon lever M are balanced and the motor is stationary, neither of its commutator-wheels being in circuit. 85

In the modification shown in Fig. 3 the commutator-wheels H and H' are attached to the regulating armature-lever. When the attraction of K preponderates wheel H' is brought into contact with the commutator-segments, 90 and so long as it remains in contact the motor revolves in a proper direction for separating the carbons. A reversal of the motor occurs when H is brought into contact with the segments, and the upper-carbon carrier is thus 95 moved in a direction to cause the carbons to approach.

In the modification shown in Figs. 4 and 5 the main and derived circuit coils T and S control the movements of a lever, 12, pivoted at 100 13, supporting on one arm axial cores for the coils, and actuating by its other arm a reversing-clutch, 14, of any approved construction, which is attached to the shaft of the worm-gear propelling the carbon, and which is made 105 to engage with either wheel 15 or 16, as the effects of the current in T or S preponderate. Wheel 15 engages directly with pinion 17 upon the shaft of the motor, which is in a continuously-closed derived circuit, and therefore 110 moves continuously in the same direction, while wheel 16 is geared to pinion 17 through wheels 21 and 22, and is thus made to revolve continuously in an opposite direction from 15. 115

The lamp is here shown as provided with the ordinary back ratchet, connected to the shaft and wheel gearing with the carbon-carrier, so that the latter may be raised freely without moving the other wheels of the train when a new carbon is to be inserted. By the above means 120 the portion of the gear-train connected directly to the carrier is made to move in either direction by the action of the electric motor, so that the carbon-carrier may be lifted to form the arc, or may be allowed to move in a downward direction to lessen the distance between it and the lower carbon, its movement in the latter direction depending upon the speed of movement of that wheel of the motor-train with which it gears. 125

When the coils S and T balance one another 130 in their effect upon the lever 12, which is the

case so long as the arc is of the proper length, the clutch is held in an intermediate position out of contact with both wheels 15 and 16.

What I claim as my invention is—

5 1. The combination of a carbon-carrier, an electric motor gearing with said carrier, so as to control its movement in both directions, said motor being placed in a derived or branch circuit, devices, substantially as described, for 10 reversing the direction of movement of that portion of the motor-train which engages with the carrier, and two regulating or controlling electro-magnets operating said reversing devices, one of said magnets being placed in a 15 derived circuit to the carbons and the other in the main or principal circuit with said carbons.

2. The combination of a carbon-carrier, an electric motor geared thereto and placed in a 20 derived or branch circuit, circuit-closing devices for reversing the movement of the electric motor, and two regulating or controlling electro-magnets for operating said circuit-closing devices, one of said magnets being placed 25 in a derived circuit to the carbons and the other in the main or principal circuit with the carbons.

3. The combination, substantially as described, of a carbon-carrier, an electro-magnetic motor gearing with the carrier and provided with two commutator wheels or brushes bearing upon its commutator-cylinder in the manner set forth, said motor being placed in a derived or branch circuit, and devices, substantially as described, which close the circuit to one or the other of the commutator-brushes, so as to reverse the direction of rotation of the motor.

4. The combination, substantially as described, of a carbon-carrier, an electro-magnetic motor in a branch or derived circuit,

geared to said carrier, a two-point circuit-closer controlled by a regulating electro-magnet, and circuit-connections, as described, from said circuit-closer to independent commutator 45 wheels or collectors upon the motor, whereby the direction of rotation of the motor may be reversed.

5. The combination of a carbon-carrier, a propelling electro-magnetic motor in a branch 50 or derived circuit, provided with a commutator-cylinder, and independent commutator wheels or collectors, applied in the manner described to said commutator-cylinder, so that the motor may be made to revolve in either 55 direction by closing the circuit through one or the other of said collectors, a circuit-closer joined to the collectors, opposing electro-magnets in the main or principal circuit and in a derived circuit to the arc, substantially as described. 60

6. The combination, substantially as described, of a carbon-carrier, an electro-magnetic motor in a derived circuit, provided with independent commutator brushes or collectors, 65 and a pivoted armature-lever, main and derived circuit electro-magnets acting upon said lever, and circuit-connections, as described, the whole so arranged that when the attraction of the main-circuit magnet preponderates the 70 circuit of the motor is closed through one of the collectors and the motor revolves in one direction, while, vice versa, when the attraction of the derived-circuit magnet preponderates the circuit is closed through the other collector 75 and the motor revolves in the opposite direction.
